APPLICATION OF LIQUID TREATING MATERIAL TO STRIP MATERIAL

Raymond B. Frost, Rutherford, N. J., assignor to
 United States Rubber Company, New York,
 N. Y., a corporation of New Jersey

Application January 19, 1943, Serial No. 472,849

8 Claims. (Cl. 91—55)

This invention relates to the application of liquid treating materials to strip material such as wire, threads, cords, and the like.

In coating wire with varnish, enamel, rubber latex, or solutions or aqueous dispersions of rubber or rubber-like materials, and in coating or impregnating threads or cords with dispersions or solutions of treating material, the usual method of applying the liquid treating material to the wire, thread, cord, or other strip material, is to lead the strip material vertically downward into a tank of the liquid treating material, pass it around an immersed sheave and then lead the strip material out vertically again to a drier or the like. The objections to this method are the large amount of liquid treating material necessary and the excessive tension on the strip material required to overcome friction of the sheave bearings. Where the sheave is immersed less than one-half its diameter in the treating bath in order to keep the sheave journals or bearings out of the bath, the strip material leaves the sheave surface on a point of contact above the surface of the bath producing irregularities in the coating.

Various methods have been suggested for applying liquid treating materials to strip material by passing the wire or thread vertically upwards through a bath of the treating material, the strip material passing through openings in the bottom of the chamber or container which holds the body of the treating material. To keep the treating liquid from flowing out of the openings in the bottom of the container or tank through which the strip material passes, wiping or sealing elements have been provided to make close contact with the strip material as it passes through the opening, thereby holding the treating material in the tank. Such wiping or sealing elements wear out readily, and when the treating liquid is pressure sensitive, as for example, rubber latex, the friction of the strip material passing through the wiping element tends to cause coagulation at the seal, resulting in uneven coatings with the formation of lumps of coagulum on the surface of the strip material. It has also been suggested to keep the liquid from flowing out of the apertures in the bottom of the tank by relying solely on capillary action or adhesion of the liquid, but this is unsatisfactory because slight changes in temperatures and in the composition of the liquid may cause great changes in the viscosity and other physical properties of the liquid upon which reliance must be had to maintain the seal. Another suggestion has been to maintain air pressure beneath the apertures, but in this method air

is carried along with the traveling strip, preventing smooth application of the treating liquid.

It is the purpose of the present invention to improve the application of liquid treating materials to strip material, such as wire, cord, threads, and the like, where the strip material passes vertically through an aperture in the bottom of the container for holding the liquid treating material. Other advantages will readily appear from the following description, reference being made to the single figure of the drawing which is a diagrammatic view of a preferred embodiment of the invention.

According to the present invention, a small column of the liquid treating material is prevented from flowing out of an aperture in the bottom of the chamber by maintaining a partial vacuum within the chamber, as by providing an air ejector surrounding an aperture in the top of the chamber which is aligned with the aperture in the bottom of the chamber and through which apertures the strip material passes. The air ejector at the top of the treating chamber draws air from inside the chamber through the top aperture, creating a partial vacuum in the chamber so that the treating material in the bottom of the chamber will be prevented, by the atmospheric pressure on the bottom of the liquid column, from flowing out of the bottom opening. Thus the strip material is free to pass up into, through, and out of the treating material to the surrounding space without the use of a mechanical seal, while the treating liquid is prevented from flowing out of the bottom opening.

Referring more particularly to the drawing, there is illustrated therein an apparatus for coating a single wire with a rubber dispersion, such as latex. Several of such units may be used in cascade where multiple coats of the latex are to be applied to the wire. Similarly, a number of wires may be made to pass through an apparatus by providing the requisite number of aligned top and bottom apertures as shown in the illustration. In the drawing, a wire 1 passes upward in vertical direction through an ingress opening 2 in the bottom of the chamber 3 and out through an egress opening 4 at the top of the chamber. The chamber 3 is reduced in size at the bottom to form a well 5, so as to reduce the size of the body of latex 6 which is to be maintained in the bottom of the chamber. The base 7 of the well 5 is preferably of rubber so that where wires are spliced together, the opening 2 will yield when the splice passes through. The opening 2 is larger than the wire 1 so that the base 7 does not act as a wiping

and sealing surface. Latex is kept supplied to the well 5 by the tube 8 connected to the side of the well intermediate of the column of latex as at 9, the tube 8 acting as a siphon feed from a latex reservoir 10. The top opening 4 is preferably extended upward in the form of a tube 11. A tube 12 surrounds tube 11 and is sealed to the top of the chamber 3 as at 13. An inlet tube 14 is connected to the tube 12 adjacent to the top of the container 3 for entrance of compressed air which in flowing out of the space between the tubes 11 and 12 draws air along with it through the opening 4 and out of the tube 11, as shown by the arrows, thereby producing a partial vacuum in the container 3. A radiant heater 15 for gelling and drying the latex may be provided between the bottom and top openings of the chamber.

In operation, as may be clearly seen from the drawings, the wire 1 enters the treating chamber through the bottom opening 2, passing through a column of latex 6 in the well 5 at the bottom of the chamber 3. By supplying latex from reserve to the latex reservoir 10, and maintaining the level of the latex in the reservoir at the same elevation as the bottom of well 5, the column of latex 6 may be kept at the proper level in the well. As the wire passes upward it becomes gelled or dried by means of the radiant heater 15. The wire passes out through the opening 4 in the top of the container. Air under pressure is introduced through the entrance tube 14 into the tube 12, and as the air flows upward past the mouth of tube 11, it acts as an air ejector carrying with it air drawn from the inside of the chamber 3 through the tube 11. In this manner a partial vacuum is maintained in the chamber 3, preventing latex 6 in the bottom of the chamber from flowing out through the bottom opening 2, by virtue of the atmospheric pressure acting on the latex at the opening 2.

The apparatus may be used with various liquid treating materials and for treatment of various kinds of strip materials, such as wire, thread, cords, and the like. The surface tension and adhesion of the treating liquid play an important part in supporting the column of liquid 6 in the well 5. The larger the opening in the bottom through which the wire passes, the greater is the danger of rupture of the lower surface of the treating material in the well. Therefore, for reasonable assurance of successful operation, the radial clearance between the wire and the sides of the opening 2 should generally not be greater than $\frac{3}{2}$ of an inch with low viscosity liquids. The wire, passing in an upward direction, produces an upward lifting force or drag acting on the liquid, resulting from the combined effects of the viscosity of the treating liquid and the adhesion between the treating liquid and the strip material. The chamber 3 may be of approximately the same diameter as the bottom well 5 or as the opening 4 or the exit tube 11. The heating unit may surround such a tube-like container, or if desired, the heating unit may be eliminated from the treating chamber and heat applied to the wire after egress therefrom.

In coating wire with latex as illustrated, or in any treatment with a liquid material, the treatment may be repeated any desired number of times. If the treatment results in a coating as illustrated in the drawing, it may be a permanent coating, as for example, a rubber insulation on wire. If desired, such a wire may have one or more sharp edges so that the coating may

be stripped from the wire to produce one or more rubber threads.

In view of the many changes and modifications that may be made without departing from the principles underlying the invention, reference should be made to the appended claims for an understanding of the scope of the protection afforded the invention.

Having thus described my invention, what I claim and desire to protect by Letters Patent is:

1. Apparatus for applying liquid to strip material comprising a chamber adapted to hold a body of treating liquid in the bottom thereof, said chamber having top and bottom openings for the passage therethrough of strip material, means for withdrawing air from the interior of the chamber so as to create a partial vacuum in said chamber, whereby treating liquid in the bottom of the chamber will be prevented by the pressure of the atmosphere from flowing out of said bottom opening, and means for supplying treating liquid to a body of treating liquid in the bottom of said chamber.

2. Apparatus for applying liquid to strip material comprising a chamber adapted to hold a body of treating liquid in the bottom thereof, said chamber having top and bottom openings for the passage therethrough of strip material, an air ejector associated with said chamber for withdrawing air from the interior of the chamber so as to create a partial vacuum therein, whereby treating liquid in the bottom of the chamber will be prevented by the pressure of the atmosphere from flowing out of said bottom opening, and means for supplying treating liquid to a body of treating liquid in the bottom of said chamber.

3. Apparatus for applying liquid to strip material comprising a chamber adapted to hold a body of treating liquid in the bottom thereof, said chamber having top and bottom openings for the passage therethrough of strip material, an air ejector positioned adjacent the top of said chamber for withdrawing air from the interior of the chamber so as to create a partial vacuum therein, whereby treating liquid in the bottom of the container will be prevented by the pressure of the atmosphere from flowing out of said bottom opening, and means for supplying treating liquid to a body of treating liquid in the bottom of said chamber.

4. Apparatus for applying liquid to strip material comprising a chamber adapted to hold treating liquid in the bottom thereof, said chamber having top and bottom openings for the passage therethrough of strip material, an air ejector associated with said top opening in such a manner that the passage of air under pressure through the ejector will draw along air from the interior of the chamber through said top opening to create a partial vacuum in the chamber, whereby treating liquid in the bottom of the chamber will be prevented by the pressure of the atmosphere from flowing out of said bottom opening, and means for supplying treating liquid to a body of treating liquid in the bottom of said chamber.

5. Apparatus for applying liquid to strip material comprising a chamber adapted to hold treating liquid in the bottom thereof, said chamber having top and bottom openings for the passage therethrough of strip material, an air ejector surrounding said top opening so that the passage of air under pressure through the ejector will draw along air from the interior of the chamber

through said top opening to create a partial vacuum in the chamber, whereby treating liquid in the bottom of the chamber will be prevented by the pressure of the atmosphere from flowing out of said bottom opening, and means for supplying treating liquid to a body of treating liquid in the bottom of said chamber.

6. Apparatus for applying liquid to strip material comprising a chamber adapted to hold treating liquid in the bottom thereof, said chamber having top and bottom openings for the passage therethrough of strip material, means for withdrawing air from the interior of the chamber so as to create a partial vacuum in said chamber, whereby treating liquid in the bottom of the chamber will be prevented by the pressure of the atmosphere from flowing out of said bottom opening, a heating device intermediate said openings for heating strip material during its passage through said chamber, and means for supplying treating liquid to a body of treating liquid in the bottom of said chamber.

7. Apparatus for applying liquid to strip material comprising a chamber adapted to hold treating liquid in the bottom thereof, said chamber having top and bottom openings for the passage therethrough of strip material, an air ejector associated with said top opening in such a manner that the passage of air under pressure through

the ejector will draw along air from the interior of the chamber through said top opening to create a partial vacuum in the chamber, whereby treating liquid in the bottom of the chamber will be prevented by the pressure of the atmosphere from flowing out of said bottom opening, a heating device intermediate said openings for heating strip material during its passage through said chamber, and means for supplying treating liquid to a body of treating liquid in the bottom of said chamber.

8. Apparatus for applying liquid to strip material comprising a chamber adapted to hold treating liquid in the bottom thereof, said chamber having top and bottom openings for the passage therethrough of strip material, an air ejector surrounding said top opening so that the passage of air under pressure through the ejector will draw along air from the interior of the chamber through said top opening to create a partial vacuum in the chamber, whereby treating liquid in the bottom of the chamber will be prevented by the pressure of the atmosphere from flowing out of said bottom opening, a heating device intermediate said openings for heating strip material during its passage through said chamber, and means for supplying treating liquid to a body of treating liquid in the bottom of said chamber.
